UNITED STATES PATENT OFFICE.

LÉON PLANCHE, OF PARIS, FRANCE.

DEVICE FOR ASSEMBLING THE PARTS OF PASTEBORD BOXES AND OTHER SIMILAR PACKINGS.

1,148,985.

Specification of Letters Patent.

Patented Aug. 3, 1915.

Application filed January 8, 1914. Serial No. 811,006.

To all whom it may concern:

Be it known that I, LÉON PLANCHE, a citizen of the Republic of France, residing at 130 Rue du Faubourg Saint-Denis, Paris,

5 in the Republic of France, manufacturer, have invented certain new and useful Improvements in Devices for Assembling the Parts of Pasteboard Boxes and other Similar Packings, of which the following is a 10 specification.

This invention relates to a device for assembling the parts of boxes made of pasteboard and of all other pasteboard packings, as well as those made of strong paper and 15 other similar materials, allowing of uniting simply, quickly and safely all the component parts of the body or of the lid of such packings or of their fastening flaps and the like.

20 According to this invention, there is provided in one of the parts to be assembled a slit, which may be either straight or curved, and the other part is provided with a flap or tongue enabled to engage in such slit and 25 of which the end or head is provided with lateral projections which may be folded inwardly to allow of the passage of the said flap into such slit and then folded outwardly to prevent the escape or disengagement of 30 such flap. Such device is essentially different from the assembling devices now in use in which the lateral projections of an assembling flap integral with one of the parts to be assembled are engaged in two 35 distinct slits, provided in the other part. In this case, the projections or fastening elements alone are engaged under the other or opposite part and are only held thereunder by reason of the resistance of the flap to 40 the flexion in the direction perpendicular to its plane, and as such resistance is very slight on account of the nature of the pasteboard and of the deformation to which it is often subjected to put such elements in place, 45 the result is that the assembling is not safe and gives way to the least effort made to raise the flap, especially when the edge of the latter, in the free part between the two slits, is fastened or raised by means from the 50 outside.

With the novel device the safety of the assembling is much safer and the aforesaid drawback does not occur as the slit part extends across the flap throughout its length

and prevents its being lifted either by its 55 own resistance or any outer means which cannot be inserted thereunder to lift the same.

The accompanying drawings show by way of example the application of such an assembling device to the formation of the body of a pasteboard box.

Figure 1 is a development of the parts of the box to be assembled; and Fig. 2 is a detail section of the box showing one of its 65 angles as seen from within.

In order to assemble the two sides *a* and *b* of the box the side *a* is provided with a vertical slit *c* and the side *b* is provided with a lateral flap *d* which may be engaged in such 70 slit and has projections or catches *e* turned in opposite directions. Such catches are folded inwardly before the insertion of the flap *d* into the slit *c* (see Fig. 1) and then folded outwardly (see Fig. 2) so that in 75 abutting against the adjacent parts of the ends of the slit, they prevent the flap from being separated from the same in whatever direction the efforts may be made to bring about such separation. The width of the 80 flap *d* at the tip thereof is such as to permit it to just enter the slit *c* when projections *e* are folded inwardly as shown in Fig. 1 of the drawings. In this manner the flap is prevented from shifting in the slit when in 85 engaged position. It will be observed that the projections *e* are bent inwardly on lines parallel to each other and spaced apart a distance equal to the interior dimension of 90 the slit, so as to permit the flap to enter the slit, while the slit is preferably provided with a curved central portion and straight ends so that when the flap is engaged therewith, the beveled projections will extend beyond the ends of the slit and be held from 95 displacement.

Of course, the shape and the proportions of the slit, of the assembling flap and of its catches may be varied and the present assembling device may be applied to the manufacture, to the mounting or to the closure of 100 all kinds of boxes or other packings.

Claim:

In a device for assembling the parts of pasteboard boxes and other similar packings, the combination with a body and a foldable part therefor having a slit with a curved central portion and straight ends; of

a second foldable part having a tapered flap terminating in oppositely extending beveled projections foldable inwardly to enter the slit and adapted after being passed through the slit to be extended in alinement with the flap and to project beyond the ends of the slit to prevent disengagement of the flap.

In testimony, that I claim the foregoing as my invention I have signed my name in presence of two subscribing witnesses.

LÉON PLANCHE.
